OUTPUT COUPLING CIRCUIT FOR CAVITY RESONATORS

Paul Wythe Crapuchettes, Atherton, Calif., assignor to Litton Industries, Inc., San Carlos, Calif., a corporation of California

Continuation of application Serial No. 323,268, November 29, 1952. This application December 20, 1957, Serial No. 704,203

5 Claims. (Cl. 333—33)

This invention relates to output coupling circuits for electron discharge devices having cavity resonators, and particularly to coupling circuits employing wave guides for coupling the power out of a cavity resonator, such as a resonator cavity in a magnetron oscillator. This application is a continuation of U.S. Patent application Serial No. 323,268, filed November 29, 1952, now abandoned.

The generation of microwave power at comparatively high electron efficiency is one of the inherent advantages of the magnetron. However, high efficiency may be obtained only if the coupling to the load is adjusted to an optimum value for all frequencies over the operating frequency band. The search for a broad-band system suitable for coupling magnetron generators to an output system led to consideration of wave guide coupling. Wave guides including special elements were tried, e.g., a quarter wave length section of geometric mean impedance (H section, or ridge wave guide) was employed between the output cavity of the magnetron and the wave guide. However, when the magnetron was tuned over a range of more than $\pm 5\%$, this method was not completely satisfactory. New systems were designed which employed ramps whose impedance varied exponentially, per guide wave length, from the output cavity load impedance to the wave guide impedance. At higher frequencies the load impedance requires such small spacing between the ramp sections as to render this system impractical. Thus, a system was sought which would permit the use of larger spacing between the ramp sections (when the ramps are used) and at the same time present the frequency vs. impedance characteristic required by the magnetron to operate at high efficiency.

Accordingly, it is an object of this invention to provide a coupling circuit for a cavity resonator which permits relatively larger spacing between the ramp sections and presents the frequency vs. impedance characteristic required by the magnetron.

It is a further object of this invention to provide a unique broad-band system suitable for coupling a magnetron generator to an output system, by providing cut-off wave guide sections.

It is a feature of this invention to provide a novel means for providing the desired impedance over a given frequency band in a cut-off wave guide section.

In accordance with one aspect of the invention there is provided a coupling circuit interconnecting two sections of a transmission system having different characteristic impedances. The coupling circuit comprises a wave guide equipped with impedance matching means at either ends thereof to match the impedance of the respective sections of the transmission system. The wave guide is so dimensioned that the normal frequency of the energy transmitted through said system is less than the cut-off frequency of the wave guide. The transfer of real energy through the wave guide is effected by the reflection pro-

2

duced by the different impedances at the ends of the wave guide.

The above-mentioned and other features and objects of this invention and the manner of attaining them will become more apparent and the invention itself will be best understood, by reference to the following description of an embodiment of the invention taken in conjunction with the accompanying drawings, wherein:

Fig. 1 illustrates a cross-sectional view through a multi-cavity magnetron anode and the output wave guide coupler illustrating the construction of the output coupler in accordance with my invention;

Fig. 2 is a perspective view showing in particular a feature of my invention;

Fig. 3 is a frequency-impedance curve of a cut-off wave guide; and

Fig. 4 is a graph computed from experimental data showing the efficiency using my invention as compared with the prior art.

Although the description of my invention will be made in connection with the magnetron, it is to be understood that the principle of the invention, may be utilized, with equal facility, with cavity resonators in general.

Referring to Fig. 1, there is illustrated a magnetron having an exciting cathode 1 disposed centrally of a cylindrical anode 2. A plurality of radially disposed vanes 3 are fastened at one end to the anode wall 2 to provide successive adjacent cavity resonators. Coupled to the magnetron is an output wave guide 4 comprising a conductive outer wall member 5 which may be cylindrical or any other shape and sealed at one end 6 to the wall section 2. For the sake of simplicity, only the parts necessary to an understanding of the invention are illustrated. For example, the cathode leads and the cylindrical section usually surrounding the anode wall are not shown. The magnetron resonator and the output transmission system are coupled by means of an opening such as slit 7 made in the wall 2. This slit 7 is longitudinally disposed in the cylindrical wall 2 at a radial or non-radial angle, depending on the design of the magnetron. Impedance transformer ramps 8 may be employed to control the impedance of the wave guide with respect to the impedance of the magnetron oscillator as described in my Patent No. 2,555,349, filed August 18, 1948 and issued on June 5, 1951.

The structure described above defines a known type coupling circuit for a magnetron. Further details of this type system may be found in the above-identified patent. The efficiency of a generator coupled through such a system tuned over a band of frequencies follows a curve such as shown at A in Fig. 4. This curve is for ramp section separated by .003" gap at their convergent ends, and it is seen that the efficiency diminishes materially from 1700 mc./s. to 2400 mc./s.

In accordance with the present invention, the output transmission system of the magnetron further includes a waveguide section 9 which is dimensional below cut-off at the operating frequency of the magnetron. It should be noted here that the cut-off waveguide section 9, as shown in Figs. 1 and 2, is similar to a conventional waveguide iris, the distinction between an iris and a section of cut-off waveguide being that the latter has a finite length in the direction of propagation whereas an iris has no length for practical purposes.

Consider now the function and purpose of the cut-off waveguide section as it relates to the operation of the magnetron. It is known that the attenuation factor in the propagation constant of a cut-off waveguide is real rather than imaginary as it is in a conducting waveguide, the frequency versus impedance curve for a cut-off waveguide being shown in Fig. 3 from which it may be seen

that the impedance of the waveguide decreases as the frequency approaches cut-off level. It is also known that the nature of magnetron operation is such that a fixed electrode geometry tends to require a load impedance which varies approximately as frequency squared.

The characteristic curve of the cut-off waveguide most nearly fills this requirement. Thus to attenuate the wave in a given frequency range, as for example, between points B and C, the iris ring or cut-off waveguide is provided, which may be positioned either adjacent the magnetron's anode wall, as shown in Fig. 1, or may be further removed from the magnetron sandwiched between portions of the ramp sections 8.

The opening in the cut-off waveguide 9 is chosen to form the proper impedance in the waveguide whereby the magnetron efficiency curve is in the position substantially as shown at D, in Fig. 4. The attenuation in the output transmission system is thus determined by the dimensions of the cut-off waveguide, together with the terminating impedance which is shown illustratively in Fig. 1 by the block designated 10. It should be noted at this point that the cross-sectional dimension of the cut-off waveguide will determine its cut-off frequency and its attenuation per unit length; accordingly it is apparent that the attenuation of a cut-off guide and its variation with frequency may be controlled by controlling its cross-sectional dimension and length.

With reference now to Fig. 2 it will be noted that the convergent ends of ramps 8 and the associated conducting output waveguide may be utilized to provide a reflective termination at the output end of the cut-off waveguide 9 to thereby reflect a portion of the wave transmitted therethrough. It should also be noted at this point that input to the cut-off waveguide from the cavity resonator, as shown in Fig. 1 by the slit 7, may be employed to provide an additional matching susceptance for presenting the optimum output impedance to the magnetron's resonant system.

In constructing an output structure in accordance with the present invention, the impedance is known which the output cavity resonator likes to see if the most power is to be extracted from the magnetron. In addition, an output transformer system can be designed, based upon dimensional control limitations or any other selected criteria, for transmitting energy beyond the cut-off waveguide. The conductance and susceptance of the chosen output transformer system may then be calculated, after which the desired decoupling to be provided by the cut-off waveguide may be determined, the decoupling being the ratio of the desired sending end conductance to the load or output conductance. One then selects the length and cross-sectional dimensions for the cut-off waveguide to provide a value of δl which meets the broadband requirements of the output system, keeping in mind that to obtain a change in decoupling with a change in frequency it is necessary to consider the effect of frequency on the propagation constant δ . The selection of the cross-sectional dimension of the cut-off guide then also defines its surge admittance (y_0), and thus will determine what additional matching susceptance should be shunted across the input to the cut-off guide to provide the desired impedance to the cavity resonator.

From the viewpoint of analytic simplicity, it is preferable to use a cut-off section having ramps which extend into the conducting guide since the ramp gap and energy density need not change at the junction, thus reducing discontinuity. From the standpoint of manufacturing ease, however, it is advantageous to construct the guide without ramps, but the problem of discontinuity arises and although solvable, requires the use of flux plots or empirical measurements to determine the proper dimensions in any given application.

Although the description of the cut-off wave guide output circuit has been made in connection with a cavity resonator, the underlying principle of the invention has much

broader application. For example, the cut-off wave guide may be used as an impedance interconnecting two sections of a transmission system having different characteristic impedances. In accordance with the principles of the invention, the impedance at one end of the cut-off wave guide is adjusted with respect to the impedance at the other end to permit transfer of real energy therethrough.

While I have described above the principles of my invention in connection with specific apparatus, it is to be clearly understood that this description is made only by way of example and not as a limitation of the scope of my invention as set forth in the objects thereof and in the accompanying claims.

15. What is claimed as new is:

1. An output coupling circuit for a multi-cavity resonator magnetron wherein the magnetron resonators are formed by a plurality of radially disposed vanes connected to an outer cylindrical wall, said output coupling comprising: an output structure including longitudinal conductive walls sealed at one end to said cylindrical outer wall, said magnetron wall having a communicating slit between one of said resonators and the interior of said wave guide; a pair of oppositely disposed ramps affixed to 20 said longitudinal conductive wall to provide a conducting output waveguide; and an apertured conductive block positioned in said output structure and forming a communicating opening between said ramps and said slit, the aperture in said block forming a wave guide dimensioned to 25 said longitudinal conductive wall to provide a conducting output waveguide; and an apertured conductive block positioned in said output structure and forming a communicating opening between said ramps and said slit, the aperture in said block forming a wave guide dimensioned to 30 below cut-off at the resonant frequency of said cavity resonators to provide a frequency sensitive decoupling impedance between said cavity resonators and said conducting output waveguide.

2. A broadband output structure for extracting energy 35 from a tunable multi-cavity resonator magnetron, said output structure comprising: a section of waveguide of predetermined length and internal cross-sectional dimensions positioned adjacent one of said cavity resonators, said waveguide having a cut-off frequency higher than 40 the resonant frequency of the cavity resonators; input means for transmitting electrical energy from said one cavity resonator to one end of said cut-off waveguide; and output means forming a reflective termination at the other end of said cut-off waveguide to permit energy to propagate through said cut-off waveguide, said output means including a section of ridged conducting waveguide in which the ridges are formed by a pair of tapered ramp members disposed on opposite sides of said conducting waveguide, the convergent end of said ramps 45 being contiguous with said other end of said cut-off waveguide.

3. The broadband output structure defined in claim 2 wherein said ramps are spaced from each other at their convergent end by a distance smaller than the internal dimension of said cut-off waveguide in the plane of said ramps.

4. In a microwave oscillator including a tunable cavity resonator having an aperture for extracting energy therefrom, an energy transfer circuit to permit highly efficient operation of said resonator over its frequency range by presenting a frequency dependent output impedance, said energy transfer circuit comprising: a waveguide connected at one end to said resonator and positioned to receive energy through said aperture, said waveguide 60 being cross-sectionally dimensioned below cut-off over the frequency range of said resonator; a conducting output waveguide connected to the other end of said cut-off waveguide; and means forming a non-dissipative reflecting transition between said cut-off waveguide and said output waveguide, the length and cross-sectional dimensions of said cut-off waveguide being selected to provide an output impedance to the cavity resonator of the desired magnitude and frequency dependence.

5. In a microwave vacuum tube for presenting to an output waveguide having a relatively high impedance mi-

microwave energy generated in a tunable source of microwave oscillations whose impedance is relatively low and varies approximately as a function of frequency squared, an output coupling circuit comprising: a section of waveguide dimensioned below cut-off over the operating frequency range of the microwave source, said waveguide section being connected at one end to the microwave source and at the other end to the output waveguide; and means forming a non-dissipative reflecting transition between said other end of said waveguide sec-

tion and the output waveguide, the length and cross-sectional dimensions of said waveguide section being selected to transform the impedance of the microwave source to the impedance of the output waveguide over the operating frequency range of the source.
